DOOR STRIKE

Filed March 3, 1941

FIG. 1

FIG. 3

FIG. 4

FIG. 5

INVENTOR
Ralph I. Pendleton
BY Paul O. Flehr
ATTORNEY

and has resulted in the filing of a large number of patent applications and issued patents. A great many of these have been directed to door strikes which are of conventional construction and which are not adjustable. The present invention is directed to an adjustable door strike which is of a simplified construction and which is of an improved character.

UNITED STATES PATENT OFFICE

2,350,635

DOOR STRIKE

Ralph I. Pendleton, Palo Alto, Calif., assignor of
one-sixth to Sara G. Pendleton

Application March 3, 1941, Serial No. 381,514

4 Claims. (Cl. 292—340)

The instant invention is concerned with door strikes and relates more particularly to provision of an improved, simplified strike construction of an adjustable character.

Among the objects of my invention are the provisions of an adjustable door strike construction which provides an adjustment of the door strike itself to effect a desired latching position for the latch bolt of the door, which presents the appearance of a conventional door strike, and which is of a simple and economical construction.

Other objects and advantages of the invention will be apparent from the following description of certain preferred embodiments thereof as illustrated in the accompanying drawing, in which:

Figure 1 is an elevational view of a preferred form of door strike as mounted in a door jamb.

Figure 2 is a vertical sectional view of the strike plate taken as indicated by the line 2—2 in Figure 1;

Figure 3 is a horizontal sectional view through the strike plate construction as indicated by the line 3—3 in Figure 1;

Figure 4 illustrates a modified form of the invention and is a vertical sectional view similar to Figure 2;

Figure 5 is a horizontal sectional view of the strike plate shown in Figure 4 and taken as indicated by the line 5—5 in Figure 4.

Referring to Figures 1 to 3 inclusive, a door jamb 10 of conventional construction is shown having the usual recess 11 for receiving the latch bolt of the door. The door jamb 10 is recessed about the latch bolt opening 11 to receive the base plate 12 of the door strike and to position its outer surface in flush relationship with the surface of the door jamb. The plate 12 is held in place in the usual manner by conventional screws 13 which are received in counter-sunk openings in the base plate 12.

The base plate 12 has adjustably mounted thereon a door strike 14 which is disposed in a guideway or seat provided by a recessed formed portion 16 of the base plate. Guideway 16 is formed at one side of the latch opening 17 in the plate 12. Latch opening 17 is aligned with latch bolt receiving opening 11 of the door jamb. The plate 12 may be formed of sheet metal and the portion 16 is formed inwardly from the main plane of the base plate a sufficient amount so that the outer surface of the door strike 14 lies in the general surface plane of the base plate 12 and the door jamb. The depressed portion

16 of the plate 12 may extend outwardly to the front face of the door jamb as seen most clearly in Figure 3.

The door strike 14 is of generally rectangular shape and is provided with a cam end 18 for engagement with the door latch bolt 19 which is indicated schematically in Figure 3. In order to secure the door strike 14 in an adjustable manner on the base plate 12, the portion 16 of the base plate is provided with a horizontal slot 21. Slot 21 receives a clamping bolt or screw 22 having its head disposed in a counter-sunk opening in the door strike 14 and adapted to receive a nut 23 of special construction. Nut 23 is generally T-shaped to provide a flat-sided projection 24 and opposite extensions 25 at the head of the nut. Projection 24 seats in the slot 21 to allow sliding movement of the nut during adjustment of the strike plate and to prevent turning of the nut during tightening of the bolt 22. Extensions 25 provide shoulders for clamping engagement with the inner surface of the base plate 12. The slot 21 is disposed parallel to the guideway formed by the depressed portion 16 of the plate so that the door strike 14 is firmly guided in its adjusted movement by engagement of the projection 24 in the slot 21 and by the engagement of the bevelled side edges of the door strike 14 with the complementary side surfaces 26 of the guideway as shown in Figure 2.

By loosening the bolt 22 the door strike 14 can be adjusted to the desired position to allow engagement of the latch bolt 19 of the door 35 in the opening 17 while preventing rattling of the door in its closed position. From inspection of Figure 1 it is apparent that applicant's adjustable door strike construction presents substantially the same appearance as a conventional 40 non-adjustable door strike and necessitates approximately the same amount of work for installation. At the same time a very convenient and simple form of adjustment is provided to eliminate rattling of the door in its closed 45 position.

Referring to the form of the invention shown in Figures 4 and 5, the base plate 12a of the door strike construction is generally similar to the base plate 12 shown in Figures 1 to 3 and is 50 mounted in the same manner. It will be noted that the formed portion 16a may be provided with straight-sided shoulders 31 to engage within the walls of the opening 11 in the door jamb. The door strike 14a, similarly seats in a guideway formed by the depressed portion 16a, and

to further aid in guiding the door strike's linear movement, it may be provided with V-shaped extensions 32 seating in similarly V-shaped grooves 33 provided in the depressed portion 16a.

In order to provide an entirely concealed adjustment, the door strike 14a is provided on its inner face with a tubular extension or stud 34 which is received in and guided by the slot 21a of the base plate. The tubular extension or guide stud 34 is internally threaded to receive a clamping screw 36 whose head spans the width of the slot 21a and clamps against the inner face of the depressed portion 16a of the base plate 12a.

In order to effect an adjustment of the door strike 14a, the entire assembly including the plate 12a is removed from the door jamb, and the desired adjustment of the door strike 14a is effected by loosening screw 36 and sliding the strike along its guideway to the desired position. Thereafter the entire assembly is again installed by means of the screws 13.

I claim:

1. An adjustable strike construction including a base plate for mounting on a door jamb, said base plate having a recessed guideway formed transversely thereof adjacent the latch bolt opening therein, and a strike plate mounted in said guideway for limited adjusting movement therealong, a slot in said recessed guideway, and fastening means disposed in said slot and providing means engaging both said base plate and said strike plate for clamping said strike plate in selected adjusted position on said base plate, said fastening means including a nut element formed integrally with said strike plate and having an internally threaded guide extension disposed in said slot and a screw element for threaded engagement with said nut element.

2. An adjustable strike construction including a base plate for mounting on a door jamb, said base plate having a recessed guideway formed transversely thereof adjacent the latch bolt opening therein, a strike plate mounted in said guideway for limited adjusting movement there-

along, a slot in said recessed guideway, and fastening means disposed in said slot and providing means for clamping said strike plate in selected adjusted position on said base plate, said fastening means including a tubular extension of said strike plate disposed in said slot and a screw threadedly engaged in said extension and having its head engaging the back surface of said guideway.

3. An adjustable strike construction including a base plate for mounting on a door jamb, said base plate having a recessed guideway formed transversely thereof adjacent the latch bolt opening therein, a strike plate mounted in said guideway, said strike plate having one end edge spaced from an edge of said base plate to provide said latch bolt opening, the other end of said strike plate being formed to present a cam surface to the latch bolt during closing movement of the door, a slot in said recessed guideway extending in the direction of adjustment of said strike plate, and means for fastening said strike plate in selected adjusted position on said base plate, said fastening means including a screw element and a nut element, said nut element being formed integrally with said strike plate and having a guide portion slidably disposed within said slot.

4. An adjustable strike construction including a base plate for mounting on a door jamb, said base plate having a recessed guideway formed transversely thereof adjacent the latch bolt opening therein, a strike plate mounted in said guideway for limited adjusting movement therealong, a slot in said recessed guideway, and fastening means disposed in said slot and providing means for clamping said strike plate in a selected adjusted position on said base plate, said fastening means including a tubular extension of said strike plate disposed in said slot and a screw threadedly engaged in said extension and having its head engaging the back surface of said guideway, said strike plate and said recessed guideway having complementary grooves and ribs extending parallel to said slot.

RALPH I. PENDLETON.
